UNITED STATES PATENT OFFICE.

CHARLES Y. NELLIS, OF GREENVILLE, OHIO.

DESIGN FOR A PHONOGRAPH-CABINET.

54,988.

Specification for Design.

Patented Apr. 27, 1920.

Application filed July 24, 1919. Serial No. 313,110. Term of patent 14 years.

To all whom it may concern:

Be it known that I, CHARLES Y. NELLIS, a citizen of the United States, residing at Greenville, in the county of Darke and State of Ohio, have invented a new, original, and ornamental Design for Phonograph-Cabinets, of which the following is a specification.

Referring to the accompanying drawing made a part hereof the single figure shown illustrates a perspective view of my phonograph cabinet.

Having thus fully described my said invention, what I claim as new and desire to secure by Design Letters Patent, is:

A design for a phonograph cabinet, substantially as shown and described.

In witness whereof I have hereunto set my hand at Greenville, Ohio, this 19 day of July, A. D. nineteen hundred and nineteen.

CHAS. Y. NELLIS.
